COIN CONTROLLED POSTAGE MARKING
MACHINE

George A. Ammann, Riverhead, N. Y.

Application June 11, 1934, Serial No. 730,122

12 Claims. (Cl. 194—55)

This invention relates to improvements in machines for applying postage to letters and cards, and its leading object is to provide a machine for printing postage symbols on letters or cards, which is controlled by coins, and operated by the customer, so that the required amount of postage may be paid without buying stamps, and the payments made, registered.

Another object of the invention is to provide a machine of this type with a coin controlled mechanism, by means of which only the postage value corresponding to that of the coin or coins inserted will be affixed to the letter or card.

Another object of the invention is the provision of a machine of this character with means for shifting envelopes into printing position, which will operate on envelopes and cards of different lengths.

Another object of the invention is to provide means for locking the postage imprinting mechanism against unlawful operation, which will be readily released when the coin or check of the proper size is deposited in the proper receiving slot.

25 Another object of the invention is the provision of a drop or receiving hopper for the machine, which includes a movable letter carrier, which is raised when the machine is operated to affix the proper postage symbol or meter register on the envelope or other mailable article.

A still further object of the invention is the provision of a signal which will operate only when the controlling lever is actuated the full required stroke, so as to indicate to the user that the directions have been carried out.

With the above and other objects in view the invention consists in certain new and useful construction, combinations and arrangements of parts, clearly described in the following specification, and fully illustrated in the accompanying drawings, in which:

Fig. 1 is a view in perspective, showing the machine built upon a standard letter drop box.

Fig. 2 is a side elevation of the machine, with one end of the enclosing case thereof removed.

Fig. 3 is a similar view, showing the working parts in the position they assume after operation.

Fig. 4 is a vertical sectional view, taken on line 4—4 of Fig. 2, looking in the direction of the arrows.

Fig. 5 is another vertical sectional view, taken through the coin selector mechanism and the letter carrier and drop, showing the letter carrier in its normal depressed position, and the

coin selector mechanism in position for receiving the operating coin or check.

Fig. 6 is a similar view, showing the letter carrier in its raised or printing position, and the coin selector mechanism at the end of its operating stroke.

Fig. 7 is a horizontal sectional view, taken on line 7—7 of Fig. 5, looking in the direction of the arrows.

Fig. 8 is a horizontal sectional view showing the locking plate in a shifted position, with reference to the coin selector mechanism.

Fig. 9 is a rear view, partly in vertical section, with the rear wall of the enclosing case removed.

Fig. 10 is a vertical sectional view, taken on line 10—10 of Fig. 9, looking in the direction of the arrows.

Fig. 11 is a vertical sectional view, taken on line 11—11 of Fig. 9, looking in the direction of the arrows.

Fig. 12 is a vertical sectional view taken on line 12—12 of Fig. 5, looking in the direction of the arrows.

Fig. 13 is a detail horizontal sectional view, taken on line 13—13 of Fig. 5, looking in the direction of the arrows.

Fig. 14 is a detail view, on an enlarged scale, of a cam.

Fig. 15 is a detail sectional view, in bottom plan, taken on line 15—15 of Fig. 10, looking in the direction of the arrows.

Fig. 16 is a plan view of the coin gate plate.

Fig. 17 is a bottom plan view of the markers.

Fig. 18 is a bottom plan view of the follower plate.

Fig. 19 is an enlarged sectional perspective view, showing the two rows of balls for selectively operating the counters.

Fig. 20 is a vertical sectional view, showing a modified form of the invention.

Referring to the accompanying drawings illustrating the practical construction of the invention 5 designates a standard mail receptacle or box, of the type owned and employed by the governmental post-office service, having the usual lock controlled door 6, for emptying the contents thereof.

On this receptacle the case or housing 1 for my improved postage affixing machine is mounted. This case is constructed with a letter drop opening 8, which is controlled by a pivoted valve 9. The letter or other mailable article is deposited in this opening and falls upon the normally downwardly inclined plate 10, which is pivotally supported at its upper end at 11 to the case. 55

The letters are prevented from sliding off this plate into the receptacle 5, by means of the swinging stop or abutment 12, which is in the form of a curved plate, and which is pivoted at 5 13 to the case. The concave side of the plate or stop 12 is presented to the letter drop opening, and when the chute plate 10 is in its normal receiving position, the lower end of the plate 10 will engage the lower end of the abutment or stop 10 plate 12, as shown in Fig. 5.

The chute plate 10 is equipped with a pressure pad or sub-plate 14, which is connected thereto by a plurality of spring pressed pins 15, preferably arranged at the corners of the subplate 14, 15 as shown in Fig. 15. This sub-plate 14 works through an opening 14' formed in the chute plate 10, and is adapted to provide a yielding pad for the envelope or other mailable article.

The upper ends of the pins 15 are fixed to the 20 chute plate 10, and each pin carries a nut 15a on its lower end, by means of which the coil spring 15b, which surrounds the pin, may be adjusted. The sub-plate 14 is pressed through the 25 opening 14', shown in Fig. 5, by the action of the springs, which are adapted to yield when pressure is applied against the envelope or other mailable article disposed against the upper side of the chute plate. The sub-plate is not shifted above the upper surface of the chute plate, so 30 that it will not offer any obstruction to the letter or other mailable article deposited on the chute plate.

The chute plate acts to receive the letter or mailable article and to carry the same upwardly 35 to an approximately horizontal position against the printing rams or plungers, which are arranged in the station A, to engage the upper right hand corner of the letter or other mailable article disposed against the sub-plate 14. Each 40 printing element or plunger includes the vertical rod 16, having a printing type 17 on its lower end and a head 18 on its upper end, which is engaged by the coil spring 19, the lower end of which engages the horizontal plate 20, which may be a 45 cross bar or frame, secured to the housing or case 7.

The printing plungers are arranged in two groups, one group of which consists of five plungers, which are movable independently of each other. One plunger 21 carries a printing element 21' designed to impress or print the ordinal "1" on the letter or mailable article. The plungers 22, 23, 24, carry the printing elements or plates 22', 23' and 24' on their lower ends, 50 each of which is designed to print or impress upon the letter the ordinal "1". The printing elements 21', 22', 23' and 24' are arranged in parallel order, as shown in Fig. 17, so that when all of the printing elements have been applied a row of four "1" ordinals will be impressed, as 55 1111, indicating four one cent stamps. The other plunger 25 of this group of five plungers has a printing element 25' on its lower end, to impress or print the ordinal "5", on the letter or 60 other mailable article disposed on the chute plate.

A second group of printing plungers is provided, which consists of the two plungers 26 and 27. The lower end of the plunger 26 is equipped with 65 a printing element or plate 26' and the plunger 27 is equipped with a printing element or plate 27'. The printing element 26' is designed to impress the symbols S. D. indicating Special Delivery, and the printing element 27' is designed to 70 impress the postage symbols A. M. indicating 75

Air Mail. Additional plungers may be provided, so that the machine can be adapted to any schedule of postage.

The operating mechanism includes a horizontal shaft 38, which is journaled in the casing 7. 5 On the outer end of this shaft the gear 31 is mounted, the teeth of which are engaged by the gear segment 32, which turns on the stub shaft 33, fixed to the end wall 34 of the casing 7. This gear segment 32 is equipped with an arm 35, 10 formed with a longitudinal slot 36. The chute plate 10 is equipped with a stub shaft or pintle 18a, which projects through the casing or frame wall 34, and on this stub shaft or pintle the crank arm 37 is fixed. This crank arm is formed 15 with a bearing 38, which receives the stub pin 39, which is fixed to the lower edge of the chute plate 10, and works through the arcuate slot 40 formed in the wall 34. This stub pin also works in the angular slot 41 formed in the slide 42, 20 which works between the upper horizontal fixed guide 43, fixed to the wall 34, and the lower horizontal guide 44 also fixed to the wall. These two guides may be formed directly on the wall or frame part 34. The slide 42 includes a horizontal arm 42a, to which the horizontal arm 45 is connected, through the horizontal slot 46, formed in the wall or frame part 34. The inner end of the arm 45 is supported by the upstanding finger 47 on the horizontal guide 48, secured to the intermediate frame part or wall 49. This horizontal arm 45 is equipped with an inking roller 50, pivoted to freely turn thereon. This roller is made of felt or other suitable absorbent material, and is recharged with printing ink from the 35 inverted pad 51, which is supported above the chute plate 10, well above the same. When the chute plate is in the position shown in Fig. 5 the roller will be engaged with the inking pad, and when the chute plate is raised, to an approximately horizontal position, as shown in Fig. 6, the inking roller will be shifted well past the printing plates on the depressible plungers. In its horizontal movement from the position shown in Fig. 5 to that shown in Fig. 6 the inking roller 45 will roll under all of the printing plates or elements and charge the same with fresh printing ink. The inverted pad is supplied with ink through the inclined tube 52, entrance to which is controlled by the screw 53, through a tapped 50 hole in the front of the housing.

The operation of the printing plungers is controlled by mechanism, which can be operated only by the insertion of coins of denomination corresponding to the values of the postage symbols 55 impressed upon the letter or other mailable article.

The upper end of the housing or casing 7 is equipped with a series of coin chutes. The number of these chutes and their arrangement correspond to the number of individual printing plungers, and each chute is arranged to receive and guide the coins in vertical order, as shown in Figs. 5 and 6. Below the coin receiving chutes 7a, 7b, 7c, 7d, 7e, 7f, and 7g a sliding coin carrier 55 is arranged to work on the horizontal guides 56 and 56a, between the wall or frame part 34 and the wall or frame part 49. This coin carrier 55 is equipped with gear racks 57 and 58, located on the lower side thereof, and on this coin carrier the coin gate plate 59 is slidably mounted. The shaft 30 is equipped with segmental gears 59 and 60 which respectively engage the gear racks 57 and 58. When the shaft 30 is manually rocked, by means of the hand lever 61, attached 70 75

5 to the end of the shaft 30, the two gear segments 59 and 60 will be rocked, thus propelling the coin carrier 55, to which the gear racks 57 and 58 are fixed. The gate plate 59, being slideable on the carrier 55, is carried with it as the coin carrier moves, but, as will be seen from Figures 5 and 6, its motion is limited when the ends of the gate plate strike the casing of the machine in the forward motion, and when the gate plate strikes the head 18 in the backward motion. In this manner the total travel of the gate plate is less than that of the coin carrier.

In order to prevent the operation of the machine when no appropriate coin is inserted, the
15 coin carrier is equipped with an upstanding stop pin 62, which is normally engaged by the locking plate 63, hinged at its forward end to the housing 7, immediately below the coin chutes. This locking plate is formed with longitudinal side arms
20 63a and 63b, which extend over the printing plungers, and is further equipped with a connecting cross bar 63c, located inwardly of the hinged end thereof. The body of the plate or locking device is open, so that any coin may be dropped through its receiving chute upon the
25 coin carrier 55.

The coin carrier is formed with a series of coin slots corresponding to the size and thickness of the operating coins or checks, and the number thereof. One of these slots is located under one of the coin receiving chutes.

The coin gate plate is formed with milled slots which exactly receive the operating coins, and which prevent operation when the wrong coin is inserted.

When a coin is inserted in one of the coin chutes, it will drop in the slot in the carrier plate 55 in line with the chute in which the coin is inserted, against the gate plate. Due to the relative sliding movement of the gate plate on the carrier plate, the coin inserted will not be permitted to drop through the gate plate, which is normally out of registration with the carrier plate. As the operating shaft 30 is rocked the carrier plate will be shifted inwardly, moving the inserted coin with it, and the upper circular edge of the coin will engage the cross bar 63c of the locking plate, which will be raised, thus disengaging said cross bar from the stop pin 62 of said locking plate or member, and permitting the coin carrier to move to the limit of its travel.

The final movement of the carrier plate or member will move the inserted coin directly over the head of one of the printing plungers, in position so that pressure may be applied on the coin to operate the printing plunger directly under the plunger so engaged. This operation is affected by means of the cross pressure bar 64, one end of which is pivoted at 65 to the intermediate wall or frame part 49, and the other end of which is pivotally connected to the vertical rod 66, which slides in the guide 67, fixed to the outer side of the frame wall or part 34. This vertical rod 66 is equipped with a lateral pin 68, which is engaged by the lateral pin 69, fixed to the side of the gear 31, of the operating shaft 30. When this gear has completed the first phase of its motion the lateral pin 69 thereof will engage the lateral pin or shoulder 68 of the rod 66 and the pressure bar 64 will be depressed.

The cross pressure bar 64 is equipped with a convex shoe 64a which is designed to engage the block 70, which is hinged at 71 to the cross piece or bar 72, which connects the frame parts 34 and 49 to each other. The underside of this block is

equipped with a series of metal springs 73, which are designed to have physical contacting engagement with the coins, when they are disposed directly against the heads of the printing plungers. The springs are engaged by the adjusting screws 74, which are threaded through the block 70, and which serve to secure the most effective bearing engagement between the springs and the coins. The block 70 is normally elevated slightly so that it will not be necessary to exert great manual effort to force the coins under the block and over the printing plungers. When the pressure bar is depressed by the action of the gear 31 on the vertical rod 66 the coin under the block 70 will serve to transmit any motion imparted to the block 70, by the action of the pressure bar 64, to the printing plunger engaged by the coin, which will be depressed to force its printing element or plate against the envelope or mailable article, which has been elevated by the upward movement of the swinging chute plate, so that any postage mark of the moved or actuated printing element will be impressed directly on the envelope or mailable article.

When the coin carrier is allowed to return to its initial position, the coin gate plate will allow the coin to drop, as it is moved forwardly away from a position over the operated plunger, and the operating coin will drop into the chute 75, and fall into the receptacle 76, which is equipped with a spring closed gate 77, so that the accumulated coins may be released by the lever 78 into the storage receptacle 79. 25 30

The four plungers 21, 22, 23 and 24 are equipped with arms which operate counting mechanism, and due to the fact that one, two, three or four of these plungers may be operated at one time, it is necessary that a differential operation of the counting or registering means be obtained. For this purpose the head 21a of the plunger 21 is equipped with a horizontal arm 21b, which is pivoted to said head. The outer end of this arm is provided with a pendant finger 21c, which projects into the ball trough 80, fixed at its ends to the wall 34 and the wall or frame part 49. In this trough a series of hardened balls 81 are arranged to work against the head 82 of the horizontal counter operating rod 83. A coil spring 84 is arranged between the head 82 and the end of the trough 80, which forms a bearing to allow free sliding motion of the rod 83 but prevents movement of the spring. When the plunger 21 is depressed by the action of the coin and the operation of the pressure head 64 and the block 70, the finger 21c will be forced into the trough and will displace the whole series of balls in the trough between itself and the head of the rod 83, so that motion will be transmitted to this rod equal to the thickness of the finger 21c.

The plunger 22 is equipped with a similar lateral arm 22b, having a similar pendant finger which works in the trough 80, and the two adjacent fingers are spaced apart a distance fixed by the diameter of the adjacent ball. The plunger 23 is equipped with another similar lateral arm, 23b having a terminal pendant finger for a similar purpose, and the plunger 24 is equipped with a lateral arm 24b having another pendant finger.

If two of the pendant fingers are forced into the trough the displacement of the series of balls will be twice that of the action obtained by the movement of one finger alone, as the fingers are of equal thickness. If two fingers are depressed by the simultaneous operation of two plungers, 75

then the rod 83 will be shifted twice the distance, as when it is operated by the actuation of only a single plunger of this series of four plungers. Each of the lateral arms is pivoted to its plunger head, so that it will freely turn in the direction of displacement.

A second ball trough 85 is arranged below the ball trough 80 and a series of similar balls 86 are disposed therein. In this ball trough the spring 10 propelled rod 87 is arranged to slide. The balls in this trough are displaced by the pendant fingers 25c, carried by the plunger 25, the pendant finger 26c, carried by the plunger 26, and the pendant finger 27c, carried by the plunger 27. These fingers are formed on lateral arms pivoted to the heads of the respective plungers, in the manner illustrated with reference to the plungers 21, 22, 23 and 24. The lateral finger 25c and the lateral finger 26c are approximately equal in thickness, and intended to actuate the rod 87 to operate the counter to register five cents; while the finger 27c is made twice as thick as either of the fingers 25c or 26c, so that the rod 87 will be shifted a sufficient distance to register ten cents.

The particular operating mechanism between the shiftable rods and the counters or register 88 and 89 will be explained later.

The inner end of the shaft 30 is equipped with a cam arm 30c, which projects upwardly to engage the pendant roller 90 on the sleeve or tube 91, which is shiftable on the horizontal rod or shaft 92, fixed or supported between the frame part 49 and 93. This tube or sleeve is propelled along the shaft or rod by means of the expansion coil spring 94, mounted on said shaft. On the sleeve or tube 91 the pusher rod 95 is pivoted at its upper end, so that the lower end will project into the mail drop or chute directly over the chute plate 10. The upper end of the pusher rod has pivotal engagement with the stub shaft 96, carried by the housing 7. When the cam arm 30c is swung against the roller 90, the sleeve 91 will be shifted a short distance, but due to the leverage action of the rod 95 the lower end thereof will develop a long sweeping stroke against the end of any envelope or mailable article disposed on the chute plate 10.

As a result of this arrangement any mailable article will be forced against the end of the drop 50 so that it will register with the printing plungers, and the plunger selected will impress the postage mark desired upon it. When the cam arm returns to its original position the coil spring 94 will return the tube to its initial position, and thereby return the lower end of the pusher rod 95 to the far end of the mail drop chute.

When the chute plate 10 is swung to printing position, the abutment plate 12 will be locked by the latch 98 in an open position, as shown in Fig. 6. This results from the fact that the end of the chute plate has a sliding action against the abutment or stop plate, as it swings upwardly, and when the chute and printing plate reach a position against the printing plungers, the abutment or stop plate or curtain will be swung into line with the end of the latch 98, and will be retained in latched position, as the chute and printing plate 10 returns to its initial letter receiving position. When this takes place the latch 98 will be depressed, thus releasing the abutment or stop plate which will be moved to closing position, by the action of the spring air-check 99, which will delay this closing movement sufficiently to allow 75 the letter or mailable article, as a card, to fall

from the chute plate through the discharge opening into the mail box or receptacle 5.

The underside of the chute plate 10 is equipped with a spring hook 100, which is designed to snap over the bevelled upper end of the bell hammer lever 101, which is pivoted at 102 to the housing 7. This lever is engaged by a pull spring 101a, and is adapted to strike against the bell or audible signal 103. When the operating lever on the shaft 30 is swung to the full length of its stroke, 10 and the chute plate 10 is raised to an approximately horizontal position against the printing plungers, the spring hook 100 will disengage from the bell hammer and the pull spring will actuate the hammer to cause it to engage the bell or 15 audible signal, thus indicating to the operator that the machine has been properly operated.

In order to prevent illegal coins or checks from being used, a return hopper 104 is arranged immediately under the coin receiving chutes. 20 Should the coin be undersized it will drop through the coin carrier plate and the gate plate into the return hopper 104, and the customer may regain the coin thus returned through the opening 105, which is never closed.

The coins which are accepted by the machine are observable through the coin receptacle window 16a, which is made of transparent glass, so that the public can examine the last coin used for operating the machine, or the last group of coins 30 employed for operating the machine.

Each time the machine is operated the spring closed gate 77 will be opened by the action of the lateral rod or arm 77a, which is carried by the gear segment 60, which engages the lever 78 35 when the shaft 30 rocks the gear segment 60 to shift the coin carrier inwardly over the plungers.

The lower end of the mail pusher rod works through a slot 110a formed in the shiftable chute plate 10, so that it will always have striking engagement with the edge of any card or letter, as shown in Fig. 11, instead of riding over the top of the same. The pusher rod may be made of a coil spring, closely wound, so that it can bend if the letter or card, or other mailable article is 40 very long.

When the chute plate 10 has been swung to printing position and the mailable article is thicker than the average letter, the sub-plate will yield, due to the spring posts which connect the same to the chute plate, so that excessive pressure will not be developed on the active printing plungers.

The machine may be operated by a single cent, when the proper legal coin is inserted in the proper receiving chute. The coin will drop into one of the slots of the carrier plate, and the lever can be shifted a sufficient distance to bring the upper edge of the coin into engagement with the cross bar of the locking plate or member, thus releasing the coin carrier for forward movement. If more than one coin is inserted the action will be the same. Any one proper coin will release the coin carrier and permit the full operation of the machine, but the value of the postage marked on the envelope or other mailable article will depend upon the number of coins inserted in their separate and proper receiving chutes.

If a card or envelope is to be mailed with one cent postage, only one cent is inserted in one of the penny coin chutes. If two cent postage is desired, then two pennies are inserted in separate penny chutes. If three cent postage is wanted, then three pennies are inserted in three different penny chutes. If four cent postage is desired then 75

four pennies are inserted in four different penny chutes. If five cent postage is to be marked on the letter or card, then a five cent piece, or nickel, is inserted in the single chute for this purpose. 5 If a special delivery postal marking is to be affixed, a ten cent piece is inserted in the chute for this purpose, and a ten cent piece will also operate the machine and the proper printing plunger when inserted in the chute marked A. M. 10 or Air Mail. If the proper coins are inserted in all receiving chutes at the same time, then all printing plungers may be operated at one time.

The mechanism is such that no printing plunger can be operated to impress its postage 15 mark on a mailable article, unless the proper operating coin has been properly inserted and moved above the plunger.

Additional printing plungers may be provided, to apply higher or different postage markings. 20 In this case an additional coin receiving chute would be provided for each extra plunger and the coin carrier and coin gate would be provided each with a slot to receive the coin required to operate the plunger.

25 The sub-plate 14 is constructed of base metal, or a lead alloy, and faced on the upper side with a yielding rubber plate or sheet, so that it will have the necessary silent and cushioning properties.

30 When the next succeeding customer inserts a coin or coins in the machine and operates the controlling lever, any coin or coins remaining in the receptacle 76 will be dumped into the storage receptacle 79, by the downward movement of the lateral pin 77a, which is secured to the inner gear segment. This pin engages the trip lever which operates the spring gate of the receptacle 76.

In Fig. 20 I show a modified construction, 40 wherein the valve 110 of the letter drop 111 is provided with a small lug 110a, which is engaged by the end 112 of a lever pivoted at 114, to provide a short arm 115 and a long arm 116. The long arm 116 is pivotally connected to the link 117, which is pivoted at its lower end to the latch bar 118, which is acted upon by the leaf spring 119. The end of this latch bar is formed or provided with a latch element 118a, which engages the lower end of the abutment or stop plate 120, 45 which is hinged at its upper end and which is formed with a concave inner face, against which the chute and printing plate 121 is adapted to ride. The stop plate 120 is provided with a short arm 120a, which is engaged by a pull spring 50 120b, secured in place to the housing 7a at one end, so that when the latch bar 118 is depressed the spring 120b will pull the stop plate 120 from normal open position to closed or retaining position, against the lower end of the chute and 55 printing plate 121.

The short arm 115 of the lever 113 is pivotally connected to the lower end of the short link 122, which is carried by the vertical rod 123. The upper end of this rod is pivotally connected to 60 the arm 124 of the lever 125, the other arm of which projects into the path of the coin receiving chute 126. This arm 124 may be provided with a terminal cross piece 127 to be engaged by any coin or check inserted in any coin receiving chute. The arm 124 of the lever is provided with a lug 124a, which is designed to engage the coin carrier 128, and prevent its operation, unless a coin has been inserted in the chute, or any other chute. 65

70 On the insertion of a coin in any chute the

lever 125 will be rocked, so that the arm 124 will be raised, thereby raising the vertical rod 123, and elevating the short arm 115 of the release lever 113, so that the drop valve 110 may be opened. The approximate instant that the drop valve is released by the rocking of the lever 113, the stop plate will be released, so that the pull spring 120b will pull the stop plate 120 into letter retaining position, so that the chute plate 10 can be elevated by the action of the operating lever to an approximate horizontal position, against the printing elements on the plungers. The machine would be constructed with reference to the other features of construction, as previously described, and would operate as previously described, except that in the showing of Fig. 20, no letter could be admitted to the machine, except on the insertion of a coin; and no waste papers could be dropped into the chute, except by the insertion of a coin. This would virtually prevent boys and other mischievous makers abusing the machine.

I claim as new:

1. A machine for marking postage on mailable articles, consisting of a series of printing plungers, a coin receiver arranged to receive a plurality of coins edgewise shiftable into registration with the plungers, a locking device for preventing unauthorized movement of the receiver adapted to be actuated by any coin, means for guiding coins to the receiver so that they are received edgewise, and means for applying pressure on the coins in the receiver when the receiver is in registration with the printing plungers to actuate any printing plungers engaged thereby. 25

2. A machine for marking postage on mailable articles, consisting of the combination set forth in claim 1, including means for releasing the coins from the receiver after operation of the printing plungers. 35

3. A machine for marking postage on mailable articles consisting of a printing element, a single mail carrier adapted to receive said article and move the same to position to be printed by said printing element, a coin carrier for moving coins from a receiving position to a position in line with said printing element, means for engaging said coins to move the same against said printing elements to cause the same to print postage markings upon the articles and means releasable by the insertion of a coin for locking said coin carrier against movement and means for releasing the coin from the coin carrier after actuating the printing element. 40

4. A machine for marking postage on mailable articles, consisting of a swinging mail carrier, a coin carrier, means for locking the coin carrier against movement which is released by the insertion of a coin in the coin carrier, a series of printing elements arranged to be operated when coins are inserted in the coin carrier, a pressure bar for engaging such coins to operate the printing elements, and mechanism for operating the mail carrier and coin carrier and the pressure bar in timed relation to each other. 55

5. A machine for marking mail with postage of different values, consisting of a series of independent printing elements, coin carrier means for moving coins of different values into line with the elements with the edges of the coins presented to the printing elements, a pressure bar for depressing the coins against the printing elements, and means for operating the coin carrier and the pressure bar to print postage of different values on mail disposed against the printing elements. 70

6. The combination set forth in claim 5, in- 75

cluding a mail receiver shiftable against the printing elements on the operation of the said last means.

7. A machine for marking mail with postage, 5 consisting of a series of printing elements for producing different postage markings, means for presenting coins of different values edgewise to the elements, a mail receiver movable against the printing elements, a pressure bar for applying pressure on the coins to actuate printing elements engaged thereby, and means for operating the receiver and the pressure bar in synchronism.

8. The combination set forth in claim 7, including a lever for operating the receiver and pressure bar and gear mechanism operated by the lever for causing the receiver and the pressure bar to work in synchronism.

9. A coin controlled mechanism for marking 20 postage, consisting of means for marking various postage values on mail, a coin receiver having different coin holders in which coins of different value may be inserted corresponding to the values of the postage markings and means for operating the coin receiver to move such coins into registration with the marking means and for forcing the coin against the marking means to produce postage marks on mail corresponding to the values of the coins inserted in said coin 25 receiver.

10. A mechanism for marking mail consisting of selective means for marking different postal values on mail, means for moving coins in edge-wise relation to said selective marking means, means for operating the marking means through the medium of coins carried by said moving means, and means for moving mail against the markers.

11. A mechanism for marking mail consisting of selective means for marking different postal 10 values, a coin holder constructed to present coins in edgewise relation to the marking means, means for moving mail against the markers, and means operated by said mail moving means for actuating the marking means through the medium of 15 the coins on said holder.

12. A mechanism for marking mail consisting of a series of mail markers, a coin carrier having slots in which different coins are presented in edge-wise relation to the mail markers, means for shifting the coin carrier into registration with the mail markers, a plunger movable against coins in the coin carrier to cause the coins when disposed over the markers to operate the mail markers, a mail carrier, and mechanism for simultaneously 20 operating the plunger and the mail carrier to cause the mail to be engaged by the selectively operated markers when the mail carrier is 25 operated.

GEORGE A. AMMANN. 30
